CLAIM

The ornamental design for a baby carrier, as shown and described.

DESCRIPTION

FIG. 1 is a perspective view of a baby carrier showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view of FIG. 1 to show the state after flipping down the headrest of a baby carrier; and, FIG. 9 is another perspective view of FIG. 1 to show a baby carrier with a saliva towel for reference.

The dashed broken lines in the drawings depict environmental subject matter that forms no part of the claimed design.

The dot broken lines depict stitching that forms no part of the claimed design.

The grid lines in the Figures illustrate the fabric mesh of a baby carrier.
